UNITED STATES PATENT OFFICE.

PAUL TIETGENS, OF CHICAGO, ILLINOIS, ASSIGNOR TO THE ANGELUS
PRAYER CLOCK CONCERN, OF CHICAGO, ILLINOIS, A FIRM.

DESIGN FOR A CLOCK-CASE.

SPECIFICATION forming part of Design No. 35,940, dated June 10, 1902.

Application filed March 18, 1902. Serial No. 98,848. Term of patent 7 years.

To all whom it may concern:

Be it known that I, PAUL TIETGENS, a subject of the Emperor of Germany, residing at Chicago, in the county of Cook and State of Illinois, have invented and produced a certain new and original Design for a Clock-Case, of which the following is a full, clear, concise, and exact description, reference being had to the accompanying drawing, forming a part of this specification.

My invention relates to designs for clock-cases, and has for its object the provision of a new and original design for a clock-case.

In the accompanying drawing I have shown a front view of a clock-case embodying my novel design.

The clock has a base portion *a*, with sides which incline outwardly in a downwardly direction. Two cylindrical side sections *b b* extend vertically above the base *a* and are surmounted at the top thereof by cubical portions *c c*, which in turn are surmounted by circular finials *d d*.

The roof portion of the clock is in the form of a gable, having the two sides thereof formed by semicircular portions *e e*, which project from the cubical top sections *c c*. The upper

edge of the gable terminates in a cross *f*, which surmounts the whole.

The dial *g* is located centrally in the upper 30 portion of the clock structure and is suitably provided with numerals.

Between the side sections *b b* and the top sections of the gable *e e* is arranged a door *h*, having a knob *i* and also having below the 35 dial *g* a figure representing the upper part of a cathedral-window.

The structure of the clock thus outlined presents a design in the Gothic style, the various features—such as the base, the top portions, and the design upon the door—combin- 40 ing to give it this appearance.

Having thus described my invention, what I claim as new, and desire to secure by Letters Patent, is—

The design for a clock-case, substantially as herein shown and described.

In witness whereof I hereunto subscribe my name this 13th day of March, A. D. 1902.

PAUL TIETGENS.
